UNITED STATES PATENT OFFICE

92,462

DESIGN FOR A BATTER DISPENSING PLUNGER

Ralph T. Ganary, Westmont, N. J.

Application March 28, 1934, Serial No. 51,204

Term of patent 14 years

To all whom it may concern:

Be it known that I, RALPH T. GANARY, a citizen of the United States, residing at Westmont, in the county of Camden and State of New Jersey, have invented a new, original, and ornamental Design for a Batter Dispensing Plunger, of which the following is a specification, reference being had to the accompanying drawing, forming part thereof.

In the drawing:

Figure 1 is a top perspective view of the article showing my new design, and

Figure 2 is an inverted perspective view of plunger, as shown and described.

The dominant features of my design consist of a metal grid of uniform thickness, the corners of which form a triangle, having a V-shaped guide at the edge on one side, and a plurality of depending bars attached at the corners at the bottom of the grid, having a spherical ball-shaped valve at the lower end of each bar, and a rod attached to the mid point on the bottom of the grid, partially enclosed in a depending housing tube attached thereon.

I claim:

The ornamental design for a batter dispensing plunger, as shown and described.

RALPH T. GANARY.
